(57) **CLAIM**

(21) Appl. No.: **29/115,398**

The ornamental design for a nozzle cap for foam-producing
pump dispenser, as shown and described.

(22) Filed: **Dec. 13, 1999**

DESCRIPTION

(51) LOC (7) Cl. **09-07**

FIG. 1 is a perspective view showing my new design;

(52) U.S. Cl. **D9/448**

FIG. 2 is a front elevational view thereof;

(58) Field of Search D9/300, 447, 448,

FIG. 3 is a bottom plan view thereof;

D9/449; 222/153.11, 153.12, 153.13, 153.14,

FIG. 4 is a left side elevational view thereof;

383.1, 383.2, 383.3, 384; 239/333, 538,

FIG. 5 is a perspective view of a second embodiment of my

539

new design; and,

FIG. 6 is a front elevational view thereof.

The right side elevational view is a mirror image of the left
side elevational view.

The bottom and interior of the nozzle cap form no part of the
claimed design.
